UNITED STATES PATENT OFFICE.

JOHN LATIMER, OF GILBERT PLAINS, MANITOBA, CANADA.

SHOCKING-MACHINE.

1,052,154.

Specification of Letters Patent. Patented Feb. 4, 1913.

Application filed March 13, 1909. Serial No. 483,332.

To all whom it may concern:

Be it known that I, JOHN LATIMER, of the village of Gilbert Plains, in the Province of Manitoba, Canada, have invented 5 certain new and useful Improvements in Shocking-Machines, of which the following is the specification.

My invention relates to shocking machines and the object of the invention is to 10 provide a machine which can be easily attached to the present binding machine and be operated thereby, and which will receive the sheaves thrown from the binder deck, collect them, and deposit them butts down 15 in a shock on the field, the machine being under the control of a single operator.

My invention further specifically resides 20 in the following features of construction, arrangement, and operation as will be hereinafter set forth, with reference to the accompanying drawings, in which—

Figure 1 is a plan view of the complete machine attached to the binder, a portion of it being shown in dotted outline, and the 25 parts being shown in the position assumed when receiving sheaves from the binder deck. Fig. 2 is a side elevation of the machine as in Fig. 1. Fig. 3 is an enlarged detailed perspective view of the sheaf receiving fingers showing the members controlling their operation. Fig. 4 is an enlarged detailed sectional view taken in the plane denoted by the line Y Y' Fig. 1 and looking in the direction of the arrow. Fig. 30 5 is an enlarged detailed sectional view taken in the plane denoted by the line Z Z' Fig. 1 and looking in the direction of the arrow. Fig. 6 is an enlarged detailed vertical sectional view taken in the plane denoted by the line X X' Fig. 2 and looking 35 in the direction of the arrow. Fig. 7 is an enlarged detailed plan view of the extending end of the shocking machine showing the operation of the finger supporting tray. Fig. 8 is an enlarged detailed perspective 40 view of the brackets 32 and the shaft 32'. Fig. 9 is an enlarged detail view similar to Fig. 5, showing the position of the lug 61' away from the faces of the collar, and the 45 tooth 63' withdrawn.

In the drawings like characters of reference indicate corresponding parts in each figure.

1 represents the main or bull wheel of a 50 binder and 2 a cross bar of the binder frame

on which are bearings for the main wheel as is usual.

3 represents the main drive shaft of the binder which is fitted with a bevel pinion 4 intermeshing with a second bevel pinion 5 60 carried on the shaft 6 which operates the binder teeth.

7 and 8 are the two extending main beams of the shocking machine secured at their one end to the cross beam 2 and interconnected 65 at their opposite ends by a cross beam 9. These beams are preferably formed from channel iron, and those 7 and 8 are substantially parallel.

For convenience in description I will designate the end of the machine at which the beams 9 appear as the outer end.

10 is a carriage wheel mounted on a shaft 10' which is carried on a suitable bearing 10' fastened securely to the under face of 75 the beam 9. The wheel supports the beams and is placed to the outer side and centrally of the beam 9.

11 represents the deck for the sheaves, such part being a portion of the usual 80 binder and requiring no further description. The deck inclines from the binder toward the shocking machine and appears directly above the inner end thereof.

12 12' are vertically extending uprights 85 or standards spaced apart and having the uprights 12' slightly longer than those 12. The uprights are secured at their lower ends firmly to the beams 7 and 8 and toward the inner end of the machine and are connected 90 at the top by cross beams 13 which on account of the variance in the lengths of their supporting beams incline upwardly toward the outer end of the machine. The beams 13 are preferably formed from channel iron 95 and are of an equal length, each with one end overhanging the beams 12'.

14 are suitable bearings secured to the upper side of the inner end of the beams 13 such bearings carrying a cross shaft 14' 100 from which extend two arms 14' for a purpose hereinafter explained.

15 are second bearings secured to the upper side and at the outer end of the beams 13 such bearings receiving a second cross 105 shaft 15' which is parallel to the shaft 14'.

15' are bars secured firmly at 15' to the shaft 15' and having their ends extending normally toward the shaft 14'. The bars are for initially receiving the sheaves from 110

the binder and are consequently placed a suitable distance apart for this purpose.

16 are vertically extending stop bars secured to the bars 15² adjacent the shaft 13² and directly opposite each other. These bars are of a length sufficient to effectually prevent the passage of a sheaf along the former bars and serve further to deliver the sheaves to the fingers, as will later become 10 apparent.

It is to be noticed that the inner ends of the beams 13 appear directly below the deck 11 of the binder.

17 are bearing brackets secured firmly to 15 the outer face of the beam 7 and they carry the shocking machine drive shaft 17', at the inner end of which appears a gear wheel 17² which is operated by a gear chain 17³ passing around the gear 17⁴ keyed on the 20 shaft 3. I have shown a second connection for driving the shaft 17', such being a chain 18 passing over the chain gear 18' on the shaft 17' and a second chain wheel 18² on one end 25 of the shaft 10'. However in actual practice one or the other of the drive chains 17³ and 18 will be dispensed with, that which is found the most convenient and serviceable being used. In the one instance the shaft is driven by the binder and in the 30 other by the carriage wheel 10.

19 is a counter shaft mounted in suitable bearings 19' carried on the upper side of the beams 7 and 8, respectively. The shaft is supplied at one end with a bevel pinion 35 19² meshing with a bevel wheel 19³ keyed on the shaft 17.

20 is a second shaft carried in bearings 20' secured on the upper face of the beams 7 and 8, such shaft extending at one end 40 and being provided with a crank arm 20² which is directly connected through a link 20³ with a corresponding crank arm 20⁴ at the end of the shaft 15'.

21 is a reinforcing cross beam secured at 45 its ends to the beams 7 and 8 and appears substantially centrally of the length of the machine, and 21' is a reinforcing cross bar parallel to the beam 21 secured to the beams 7 and 8 and toward their inner ends. 21² is 50 a longitudinal bar secured at its ends to the beam 21 and the bar 21' being placed nearer the beam 8 than 7.

22 is a gear wheel mounted loosely on the shaft 19 and prevented from longitudinal 55 displacement thereon by suitable shoulders on the shaft. The gear carries the male member 22² of a clutch which is designed to engage with the female member 22² which is feathered on the shaft being rotatable 60 therewith and slideable thereon. The female member of the clutch is channeled at 22³ to receive the forked end 24 of a clutch bar 25 which is pivoted at 24² to a cross bar 25 passing between the beams 21² and 7. The 65 free end of the clutch bar passes over the

upper face of the bar 21' and extends therebeyond and has a coiled spring 26 secured thereto, the opposite end of the spring being fastened to the bar. The spring is designed to throw the female member of the clutch continuously out of engagement with the male member. 70

27 is a gear wheel keyed on the shaft 20 and directly in alignment with the gear 22 to which it is connected by a chain 27'. 75

28 and 28' are similar upper and lower parallel cross bars secured at their ends to the uprights 12 and provided centrally with enlargements through which pass vertically directed openings 28², substantially rectangular in cross section, the upper opening being considerably larger than the lower one. These openings appear in vertical alignment and receive the clutch controlling bar 29 slidably, the bar entering the lower opening snugly and being free to oscillate sideways in the upper opening. The bar has a tapering lower end as at 29', the face of which bears against the free end of the clutch bar 24' so that when the clutch controlling bar is thrown upwardly the female member of the clutch is released from engagement with the male member and upon its downward movement is engaged. 80 90

30 are standards secured on the bar 25 95 and receiving pivotally the end of a link 30', the free end of which is secured by a pin to a vertically extending arm 30² pivoted to the end of a horizontally extending pin 30³ fastened to the bar 29.

31 is a cam keyed on the shaft 20 and immediately beneath the link 30' so that when the cam is rotated the bar 29 is automatically raised and lowered, such motion throwing the arm 30² controlling the upward and downward movement of the bar 29. 100 105

32 are angle shaped brackets supporting the shaft 32' which has an enlarged center 32² in which is an opening 32³ through which passes the extending end of a bifurcated rod 33 fastened at 34 to the lower end of the clutch controlling bar 29. 110

35 is a spring encircling the rod and interposed between the enlargement 32² on the shaft 32' and the forked end of the rod. 115 The purpose of the rod and spring is to hold the bar 29 in its alternative positions, that is, when the bar is passed upwardly the spring will tend to force it quickly, as soon as the rod 33 passes out of the horizontal position. The same action takes place when the bar passes downwardly, the spring operating to force it down as soon as the rod passes out of the horizontal position. 120 125

36 is a cam on the shaft 14', such cam being adapted in the rotation of the shaft to engage with the upper end of the bar 29 in one position, and to pass the bar in the other position. 130

- 36' is a spring or such like secured to the cam and to the cross bar 28, the spring tending to hold the arms 14² in their upright position.
- 37 is a chain wheel loosely mounted on the shaft 19 directly opposite the gear 22 and it carries the male member 37' of a clutch. The wheel is prevented from longitudinal movement on the shaft by any suitable means.
- 37² is the female member of the clutch feathered on the shaft and adapted to engage with the male member of the clutch. The female member is provided with a peripheral groove 37³ which receives the forked end of the clutch bar 38, the rear end of which is pivotally secured at 38' to the bar 21'.
- 38² is a spring fastened at its ends to the bars 38 and 21, respectively, such spring tending to hold the members of the clutch normally out of engagement.
- 39 is a vertical shaft supported in suitable bearings 39' bolted firmly to one of the uprights 12. The shaft has upper and lower projecting arms 39² and 39³, respectively, such arms being at right angles to each other, the upper one being connected by a link 40 to the bar 29 about midway of its length.
- 41 is a bell crank having a long and a short arm and pivoted at 41' to the upper face of the bar 25. The short arm of the bell crank is connected through a rod 41² with the clutch bar 38 and the long arm is connected through a link 41³ with the arm 39³.
- 42 is a link secured at its one end to the arm 39³ and passing to any suitable foot lever placed on the binding machine within convenient range of the operator. In this way the operation of the clutch and the side movement of the bar 29 is controlled by the operator from the binder, it being noticed that the turning of the shaft 39 by the arm 39³ causes the link 40 to pull the bar 29 sidewise, the upper end passing to a position in which it is free of the cam 36 when the cam is rotated.
- 41^x is a beam passing between the beams 9 and 21, and 42^x is a horizontal stationary finger supporting platform carried above the beams at the outer end of the machine by brackets 42'. The edge of the platform forms at one side a track at 42² which gradually departs from the center of the platform to a point shown at 42³, Fig. 7. The departure is more pronounced or rapid at 42⁴, the purpose of which will be shortly explained.
- 43 is a guide rail secured to the outer edge of the platform and having the body portion thereof throughout its length an equal distance from the track.
- 44 is a shaft mounted at its lower end in suitable bearings formed in a cross beam 44' passing between the beams 41^x and 8. The shaft extends vertically upwardly through what might be termed the center of the platform and its upper end appears at 44² (as shown in Fig. 3) and is some distance above the level of the upper face of the platform.
- 45 is a crank shaft carried in suitable bearings 45' secured to the beams 4 and 41^x and 46 is a chain gear keyed on the crank shaft and connected through 46' with the wheel 37.
- 47 is a pinion on the shaft 44 and beneath the platform, and 48 is a rack centered at 48' on a pin extending upwardly from the beam 41^x, such rack engaging with the pinion 47 and having an extending arm 49 which is secured through a link 50 with the crank shaft 45.
- 51 is a bar rigidly secured to the upper end of the shaft 44 which it will be noticed is formed with a shoulder so as to hold the bar clear of the platform.
- 52 is an end piece secured centrally to the bar and passing at right angles thereto, and to the ends of the end piece are fastened bearings 52' which receive a shaft 53, the shaft extending considerably beyond one of the bearings for a purpose herein-after explained.
- 54 is a cross bar firmly secured to the under face of the bar 51 toward the end piece 52. The bar 54 has its ends cut at an angle and is supplied with stub axles 54' which pass from each of the ends. On the axles are mounted rollers 55 which operate on the upper face of the platform 42^x when the bar 51 is turned on the shaft 44. At the opposite end of the bar 51 from the end piece 52 is a lever arm 56 which is forked and secured at its forked end to the bar 51 by a suitable pin.
- 57 is a roller carried on an axle 57' extending downwardly from the bar 56, the roller being designed to operate on the track 42², being held to the track by the rail 43.
- 58 is a lever arm secured to the shaft 44 immediately beneath the bar 51 and above the shoulder on the shaft.
- 59 is a link pivoted at 59' to the arm 58 and having its two ends forked and secured the one to the extending end of the arm 56 and the other to a bar 60 which is in turn pivotally secured to a rocker arm 61 centered on the shaft 53 and rotatable thereon. The rocker arm carries an extending lug 61' which operates between the faces 62 of a partial collar 62' firmly secured on the shaft 125 by a key 62² adjacent one of the bearings 52'.
- The object of the lever arm 58 is to prevent the link 59 from interfering with or dragging on the platform when the rocker arm swings downwardly and keeping the 130

link horizontal prevents any possibility of the roller being run off the track.

63 is a dog pivoted at 63' to an extension of the link 61, the tooth 63² of the dog being adapted to enter between one of the faces 62 of the collar 62' and the adjoining face of the lug 61'.

The dog is tripped by its free or extending end engaging with a trip bar 64 fastened at its end to the bar 51.

65 is a spiral spring secured at one end to the face of the dog 63 and at the other to the body of the rocking bar 61, the tendency of the spring being to continuously press the tooth of the dog into engagement.

66 is a sleeve on the extending end of the shaft 53, the sleeve being rotatable thereon and prevented against longitudinal displacement by a pin or any other suitable means.

67 is a second dog pivoted at 67' to the body of the rocker arm 61, such dog having a tooth or projection 68 thereon which is adapted to enter a notch 68' formed at the adjoining end of the sleeve.

69 is a spiral spring secured at its ends to the dog 67 and the rocker arm 61 respectively, its purpose being to continuously press the tooth into the notch. The dog is provided with an extending arm which is designed to engage with the under face of the stop bar 64.

70 is a bar pinned to the shaft 53 midway between the bearings 52'. The bar extends across the platform resting normally centrally on the upper end of the shaft 44.

71 and 72 are arched fingers secured centrally of their length to the bar 70 being spaced apart a distance somewhat less than the length of a sheaf. The fingers are positioned normally so as to receive the sheaves deposited by the bars 15².

73 are bearings secured to the fingers at their ends and supporting a cross shaft 74, to which is secured centrally a further arched finger 75 designed to coöperate with the other fingers to hold the sheaves prior to their being deposited in the form of a shock.

76 is an arm secured to the shaft 74 and its extending end is secured to the upper end of a link 27, the lower end of which is fastened to an arm 78 secured to the sleeve 66 and rotatable therewith.

79 is a cam on the shaft 19 such cam being adapted in the rotation of the shaft to engage with a bar 80 pivoted at 81 on the upper face of the beam 7. A link 82 connects the extending end of the bar with the long arm of the bell crank 41.

In order to better understand the shocking machine I will now describe its operation assuming the parts to be in the position as shown in Figs. 1 and 2.

65 The forward movement of the binding

machine and the shocking machine causes the shaft 3 to rotate which operates the shaft 17' which drives the counter shaft 19. As in Figs. 1 and 2 the arms 14² have been thrown down and consequently the cam 36 has engaged with the upper end of the bar 29 and forced it downwardly thereby throwing the female member of the clutch into engagement with the male member. For this reason the gear wheel 22 is rotated, consequently the shaft 20 is operated. In the figures referred to the bars 15² are about to pass upwardly, and it will be understood that prior to this motion the sheaf has been thrown onto them and rests against the bars 16. The female member of the clutch remains in engagement with the male member till the bars 15² assume the position shown in dotted outline in Fig. 2 and return to the horizontal position thereby depositing the sheaf on the fingers 71 and 72. This movement is caused by means of the link 20³ and requires one complete revolution of the shaft 20. As the bars 15² are returned to the horizontal position the cam 31 engages with the link 30' and forces it gradually upwardly, the parts being arranged so that when the bars 15² have returned to the horizontal position the bar 29 has been thrown to its upper position by the arm 30² which is operated by the cam. As soon as the bar 29 passes upwardly the clutch bar 24' is operated by its spring and the female member of the clutch is thrown out of engagement with the male member and the shaft 20 stops rotating.

It is to be understood that as soon as a sheaf is delivered over the arms 14² they return to the upper position being actuated by the spring 36'. A second sheaf passing over the deck 11 carries the arms 14² again downwardly and the cam 36 engages with the upper end of the bar 29 which it will be remembered has been returned to its upper position and carries it again downwardly throwing the members of the clutch into engagement. The second sheaf is deposited on the fingers 71 and 72 by the bars 15² in the same manner as the former one and as soon as they return to the horizontal position the clutch is disengaged in a similar manner. This motion is repeated until such time as it is considered by the operator that there are sufficient sheaves in the fingers to form a shock. At this time he presses the foot lever controlling the link 42. When the link is pulled the shaft 39 is rotated and the link 40 swings the upper end of the bar 29 sidewise in the opening 28² so that it is free of the cam 36, consequently there is no possibility of the clutch controlling the bars 15² being operated as it depends entirely upon the longitudinal displacement of the bar 29. At the same time that the link 40 is pulled the bell crank 41

is turned so that the clutch bar 38 is thrown so as to engage the female member 37² of the clutch with the male member 37¹. Consequently the gear 37 is rotated as also the 5 gear 46 which through the crank shaft 45 and the link 50 swings the arm 49 of the rack outwardly and inwardly which turns the shaft 44 one-half a revolution and back again. The shaft carries with it the bar 51 and consequently the fingers which in the 10 half rotation of the shaft pass from the position shown in Figs. 1 and 2 to the position shown in Fig. 3. In other words the fingers 71 and 72 are completely reversed and then 15 thrown to a position in which one is vertically above the other and while this motion is taking place the finger 75 is in the first instance closed down and then thrown completely back. This is accomplished in 20 the following manner: The positions which the lug 61' and the rocker arm 61 occupy at this time is shown in Fig. 9 of the drawings, it being noticed that the lug is away from the faces of the collar, and the tooth 25 63² is withdrawn, the end of the dog 63 being engaged with the trip bar 64. The gradual pull of the bar 60 on the lower end of the rocker arm turns the rocker arm on the shaft 53 and as the dog 67 is carried by the 30 rocker arm it moves with it and causes the sleeve 66 to rotate on the shaft, the tooth 68 of the dog being within the notch 68' of the sleeve. This causes the finger 75 to close over the shock within the basket as the arm 35 78 carried by the sleeve controls the finger 75. As the bar 51 continues to swing and the rocker arm to turn, the extending end of the dog 63 is gradually released from the trip bar 64 until the tooth 63² passes into 40 the opening appearing between the lug 61' and the face of the collar; that is, into the position shown in Fig. 5 of the drawings. Upon the said tooth reaching this position the rocker arm 61 and the shaft 53 are 45 locked together with the result that the shaft 53 is rotated and the bar 70 is thrown upwardly. Such bar is actuated quickly during the latter part of the turning motion of the bar 51 by the roller which is forced 50 quickly away from the center of the tray owing to the peculiar form of the track. Immediately the bar 70 assumes the upright position the finger 75 is released as the dog 67 engages with the under side of the trip 55 bar 64 and causes the tooth 68 to free itself from the notch 68' in the sleeve. This frees the sleeve and in so doing releases the finger 75, which finger is swung backwardly by the deposited sheaf as the machine advances. Upon the return motion of the 60 roller 57 the rocker arm is forced in the opposite direction by the link 60 and as the rocker arm is locked to the shaft by virtue of the tooth 63² and the lug 61' co-operating 65 with the collar 62', the bar 70 is accord- ingly returned to the original horizontal position so that the basket is brought to shock receiving position on the tray. When the roller begins to return the extending end of the dog 67 is released from the trip bar 64, 70 and later, during the rotation, the tooth 68 re-enters the notch 68' in the sleeve. It is here pointed out that as the rocker arm 61 initially swings backwardly it carries the dog 67 with it and consequently rotates the 75 tooth 68 in a right hand direction so as to allow the tooth to re-enter the notch in the sleeve, which notch has been previously turned in a right hand direction with the sleeve by the deposited sheaf swinging the 80 finger 75 backwardly in clearing from the basket. Consequently the finger 75 is swung wide open and the basket is ready to receive sheaves when it is returned to the 85 original position.

The parts are so adjusted that the bar 70 is in reality swung to the horizontal position before the dog 67 is freed sufficiently from the trip bar to allow the tooth thereof to enter the notch 68' in the sleeve as it will 90 be seen the bar is down during the first quarter revolution of the bar 51 on the return motion. The extending end of the dog 63 is engaged with the upper face of the bar 64 after the shaft has returned one 95 quarter turn, that is, when the roller has left the inclined portion of the track, so that upon the continued (back) motion of the roller, the tooth 63² is withdrawn from engagement with the face 62 of the parti- 100 tioned shoulder, and the lug 61' is freed so as to allow the rocker arm to rotate freely on the shaft 53.

It is to be borne in mind that when the bar 70 reaches its horizontal position the 105 fingers 75, which are already open, having reached the limit of their movement, the sleeve 66 ceases to rotate and as the tooth 63² is at this time withdrawn from the par- 110 tial collar as above explained the dog 67 is carried back by the rock shaft turning, fur- ther, so that the tooth 68 again engages the notch 68' and the parts are returned to the 115 original position as shown in Fig. 9.

Just at the time the fingers return to 115 their original position the cam 79 on the shaft 19 engages with the lever or arm 80, which through the link 82, the bell crank 41, the link 41², and the clutch bar 38 throws the female member 37² out of engagement 120 with the male member 37¹ of the clutch which stops the motion of the shaft 19 and, consequently of the fingers. This same motion operates the link 40 and throws the bar 29 directly beneath the cam 36 so that when 125 the next sheaf passes from the deck 11 the bar is forced downwardly and the members 22¹ and 22² of the other clutch are brought into engagement thereby throwing the sheaf 130 on the bars 15² onto the fingers 71 and 72.

It will of course be understood that the foot lever to which the link 42 is connected is not fastened but simply held down by the foot of the operator, who as soon as he 6 feels on his foot the pressure caused by the cam 79 allows the foot lever to pass upwardly, or to its free position.

In the above description relating to the 10 operation of the cam 31 in conjunction with the motion of the forks it is explained that although the members 22' and 22² are disengaged as soon as the bar 29 reaches its upper position yet it is possible for the bar to be immediately thrown down by the 15 cam 36 striking it as the cam 31 is carried away from the link 30' by the weight of the bars 15² which have not returned completely to their horizontal position at the time the member of the clutch is disengaged. It is 20 necessary that the cam 31 be turned away from the link 30', otherwise it would be impossible for the bar 29 to be forced downwardly and it is further necessary that this motion be caused by the weight of the bars 25 15² for the reason that as soon as the clutch is thrown the shaft 20 stops rotating. The bars 15² are held in their normal position by the links 20² and the crank arm 20² being in what might be termed the dead center position, that is, the one immediately to the side of the other.

What I claim as my invention is:

1. In a shocking machine the combination 35 with a binding machine, the binder deck, and a frame formed from suitable beams connected to the binding machine, of pivoted bars adapted to receive the sheaves from the deck, means for swinging such pivoted bars upwardly about their pivot so as to deposit 40 the sheaves; a lower set of fingers adapted to receive the sheaves deposited from the pivoted bars, the fingers being supported in such a manner that they remain in the same relative position to each other and means 45 whereby said fingers can be turned bodily a half turn while in a horizontal position and during such motion brought to an upright position whereby the sheaves carried thereon are in a position to be deposited on 50 the ground; a further finger co-operating with the former fingers and binding the sheaves in position during a portion of the motion and releasing from the sheaves prior to the time they are deposited on the ground; 55 and means whereby the pivoted bars are retained inactive during the motion of the fingers, as and for the purpose specified.

2. In a shocking machine, the combination 60 with suitable beams forming the supporting frame thereof, and pivoted bars adapted for the delivery of sheaves, of a vertically extending shaft carried by the frame, a horizontal bar secured to the shaft and rotatable therewith, a rotatable cross shaft 65 passing at right angles to the bar and sup-

ported therefrom; a second bar firmly secured to the latter shaft and designed to turn in a vertical direction when the shaft is rotated; fingers semi-circular in shape secured firmly to the second bar, said fingers being adapted in their normal position to receive the sheaves deposited by the pivoted bars; means for rotating the vertically extending shaft; and disengageable means for rotating the cross shaft, as and for the 70 purpose specified.

3. In a shocking machine, the combination with suitable beams forming the supporting frame thereof, and pivoted bars adapted for the delivery of sheaves, of a vertically directed shaft carried by the frame, a cross bar secured to the shaft and rotatable therewith, a cross shaft mounted in suitable bearings carried by the bar; a second bar secured to the cross shaft and rotatable therewith; a set of upwardly directed semi-circular fingers secured centrally of their length to the second bar and spaced apart, such fingers being adapted in their normal position to receive the sheaves deposited by the pivoted bars; means for rotating the vertical shaft; releasable means for rotating the cross shaft; bearings carried by the former fingers, a cross shaft mounted in the bearings, a complementary finger secured to the cross shaft, and means whereby such finger can be thrown forwardly and backwardly to bind and release the sheaves, as and for the purpose specified.

4. In a shocking machine, the combination 100 with suitable beams forming the supporting frame thereof, and pivoted bars adapted for the delivery of sheaves, of a platform firmly secured to the framework; a vertically extending rotatable shaft passing upwardly 105 through and substantially centrally of the platform, a T-shaped bar above the platform secured to and rotatable with the shaft; rollers supporting the one end of the bar on the platform; a rotatable cross shaft mounted 110 in suitable bearings carried by the cross member of the bar; a second cross bar secured to the cross shaft and rotatable therewith; a set of upwardly directed and spaced fingers secured centrally of their length to 115 the latter bar and adapted in their normal position to receive the sheaves deposited by the pivoted bars; bearings secured to the former fingers, a cross shaft mounted in the bearings, a complementary finger carried by 120 the cross shaft; means for rotating the vertically directed shaft; a track formed on the edge of the platform; an arm pivotally secured to the free end of the T-shaped bar, a roller operating on the track and supported 125 by the arm; means connecting said arm with the cross shaft whereby the operation of the roller on the track in the rotation of the T-bar rotates the cross shaft; and means for throwing the inverted finger forwardly.

and backwardly to tighten it on and release it from the sheaves carried by the other fingers, as and for the purpose specified.

5. In a shocking machine, the combination with suitable beams forming the supporting frame thereof, and pivoted bars adapted for the delivery of sheaves, of a platform firmly secured to the framework; a vertically extending rotatable shaft passing upwardly through and substantially centrally of the platform; a T-shaped bar above the platform secured to and rotatable with the shaft; rollers supporting one end of the bar on the platform; a rotatable cross shaft mounted in suitable bearings carried by the cross member of the bar; a second bar secured to the cross shaft and rotatable therewith; a set of upwardly directed and spaced fingers secured centrally of their length to the latter bar and adapted in their normal position to receive the sheaves deposited from the forks; bearings secured 70 to the former fingers, a cross shaft mounted in the bearings, a complementary finger carried by the cross shaft, means for rotating the vertically directed shaft; a track formed on the edge of the platform, an arm pivoted secured to the free end of the T-shaped bar, a roller supported by the arm and operating on the track; a guard rail secured to the platform and designed to hold the roller on the track; a partial collar 75 secured to the cross shaft carried by the T-arm; a rocker arm rotatable on said shaft and having a lug thereon adapted to pass within the opening formed by the omitted portion of the collar; a dog pivotally secured to the rocker arm and having a tooth thereon designed to pass into the opening and adjacent the lug; spring means connecting the rocker arm with the dog; a sleeve rotatable on the cross shaft having 80 one end adjoining the rocker arm there being a portion of the sleeve notched away at such end; a second dog pivoted to the rocker arm and having a tooth thereon designed to pass into the notch; spring means connecting 85 the free end of the dog with the rocker arm; an arm secured to the sleeve and an arm secured to the cross shaft supporting the complementary finger, a link connecting the arms, a lever arm secured to the vertical 90 shaft; a link pivoted to the lever arm and to the arm carrying the roller; a bar connected to the latter link and to the rocker arm; a stop bar secured to and extending from the T-shaped bar, such bar being designed to engage with the extending ends 95 of the dogs to throw their teeth out of engagement; and means for rotating the vertical shaft, as and for the purpose specified.

40 and adjacent the lug; spring means connecting the rocker arm with the dog; means connecting the rocker arm with the arm carrying the roller on the track; an extending trip bar secured to the T-shaped bar 45 and against which the dog is designed to engage; means for rotating the vertically directed shaft; and means for forcing the inverted finger forwardly and backwardly to tighten on or loosen from the sheaves 50 carried by the other fingers; as and for the purpose specified.

6. In a shocking machine, the combination with suitable beams forming the supporting frame thereof, and pivoted bars adapted for the delivery of sheaves, of a platform firmly secured to the framework; a vertically extending rotatable shaft passing upwardly through and substantially centrally of the platform; a T-shaped bar above 55 the platform secured to and rotatable with the shaft; rollers supporting one end of the bar on the platform; a rotatable cross shaft mounted in suitable bearings carried by the cross member of the bar; a second 60 bar secured to the cross shaft and rotatable

therewith; a set of upwardly directed and spaced fingers secured centrally of their length to the latter bar and adapted in their normal position to receive the sheaves deposited from the forks; bearings secured 70 to the former fingers, a cross shaft mounted in the bearings, a complementary finger carried by the cross shaft, means for rotating the vertically directed shaft; a track formed on the edge of the platform, an arm pivoted secured to the free end of the T-shaped bar, a roller supported by the arm and operating on the track; a guard rail secured to the platform and designed to hold the roller on the track; a partial collar 75 secured to the cross shaft carried by the T-arm; a rocker arm rotatable on said shaft and having a lug thereon adapted to pass within the opening formed by the omitted portion of the collar; a dog pivotally secured to the rocker arm and having a tooth thereon designed to pass into the opening and adjacent the lug; spring means connecting the rocker arm with the dog; a sleeve rotatable on the cross shaft having 80 one end adjoining the rocker arm there being a portion of the sleeve notched away at such end; a second dog pivoted to the rocker arm and having a tooth thereon designed to pass into the notch; spring means connecting 85 the free end of the dog with the rocker arm; an arm secured to the sleeve and an arm secured to the cross shaft supporting the complementary finger, a link connecting the arms, a lever arm secured to the vertical 90 shaft; a link pivoted to the lever arm and to the arm carrying the roller; a bar connected to the latter link and to the rocker arm; a stop bar secured to and extending from the T-shaped bar, such bar being designed to engage with the extending ends 95 of the dogs to throw their teeth out of engagement; and means for rotating the vertical shaft, as and for the purpose specified.

7. In a shocking machine, the combination with the framework and sheaf receiving pivoted bars carried thereby, of means for turning the pivoted bars about their pivot, means for receiving the sheaves deposited by the pivoted bars to form a shock, means for simultaneously imparting a horizontal turning and a vertically directed up-ending movement to such sheaf receiving means, and means whereby the pivoted bars are rendered inactive during such movement, as 110 and for the purpose specified.

8. In a device of the class described, in combination a stationary platform having a peripheral cam way extending partially around the platform, a rock shaft extending 115 up through the center of the platform, a T-shaped bar secured to the shaft having rollers bearing on the platform, a cross shaft journaled on the T-shaped end of the bar, a sheaf receiver secured to the cross shaft, an 120

130

arm secured to the cross shaft, a bar swung on the opposite end of the T-shaped bar, a roller thereon co-acting with the camway of the platform and links connecting the bar 5 with the arm, as and for the purpose specified.

9. In a device of the class described, the combination with the main frame, a rock shaft above the frame having bars extending 10 therefrom and sheaf retaining arms above the main frame, of a clutch mechanism designed to throw the rock shaft into and out of gear and a vertically directed longitudinally 15 slideable operating bar having a beveled lower end designed to engage said clutch mechanism, said bar being operated by the depression of the retaining arms, as and for the purpose specified.

10. In a device of the class described, the combination with the main frame, a suitable 20 rock shaft located above the main frame, bars extending from the shaft, arms carried by the bars, and a clutch mechanism provided with a suitable operating lever designed 25 to throw the rock shaft in and out of gear, of a vertically directed longitudinally slideable operating bar having a beveled lower end engaging with the outer end of the said lever to throw the clutch mechanism into gear upon its depression and means for raising the bar to its normal position, as and for the purpose specified.

11. In a device of the class described, the combination with the main frame, a rock 30 shaft above the main frame, bars extending from the rock shaft, a second rock shaft above the main frame and retaining arms extending from the latter shaft, of a clutch

mechanism provided with a suitable operating lever designed to throw the former rock shaft into and out of gear, a vertically directed longitudinally slideable operating bar having a beveled lower end engaging with the outer end of said lever, a cam on the latter rock shaft and engaging with the upper end of the bar and means for restoring the bar to the normal position after being depressed, as and for the purpose specified.

12. In a device of the class described, the combination with the main frame, a rock 40 shaft journaled above the frame, bars extending from the shaft and arms carried by the bars, of a cross shaft, a gear on the cross shaft, a clutch connecting the gear to the shaft, a supplemental shaft having a 45 geared connection to the cross shaft and a crank and link connection to the rock shaft, a cam on the supplemental shaft, an operating lever for the clutch, guideways located on the frame, a vertically directed, longitudinally slideable bar held in the guideways, having a beveled lower end engaging the operating lever of the clutch, a lever bar pivotally connected to the vertically directed bar at one end and to a suitable portion of 50 the frame at the other end and co-acting with the cam of the supplemental shaft, and means for depressing the vertical bar, as and for the purpose specified.

Signed at Gilbert Plains, in the Province 55 of Manitoba, this 30th day of December, 1908.

JOHN LATIMER.
